UNITED STATES PATENT OFFICE.

LEO G. HAASE, OF PASADENA, CALIFORNIA.

DESIGN FOR A BENCH.

48,623.

Specification for Design.

Patented Feb. 22, 1916.

Application filed August 25, 1915. Serial No. 47,339. Term of patent 14 years.

To all whom it may concern:

Be it known that I, LEO G. HAASE, a citizen of the United States, residing at Pasadena, in the county of Los Angeles and State of California, have invented a new, original, and ornamental Design for Benches, of which the following is a specification, reference being had to the accompanying drawing, forming part thereof.

I claim:

The ornamental design for a bench as shown.

LEO G. HAASE.

Witnesses:

R. S. BERRY,
JOSIAH L. GELLER.
